UNSTACKER

Ernest A. Verrinder, Riverside, Calif., assignor to
 Food Machinery and Chemical Corporation,
 San Jose, Calif., a corporation of Delaware

Application July 25, 1949, Serial No. 106,531

11 Claims. (Cl. 214—8.5)

1

This invention relates to devices for breaking down a stack of articles superimposed one upon another in the form of a column by separating the articles from the upper end of said column one at a time.

Devices heretofore provided for this purpose included an elevator for the column of articles and a separating mechanism actuated in timed relation with the elevator. The latter characteristic limited the device, with any given setting of the timed relation between the elevator and separating mechanism, to operation upon stacks of articles in which the latter have a certain fixed uniform depth. In order for the device to operate upon articles of a different fixed uniform depth, it was necessary to change the timed relation between the functioning of the elevator and of the box separating mechanism. This circumstance constituted a considerable limitation in the utility of these prior devices.

It is an object of the present invention to provide an unstacking device in which the operation of the article separating mechanism is not tied to the elevator in timed relation therewith, but wherein said device is adapted to operate upon articles varying in depth within a substantial range without any adjustment in said device to cause it to function satisfactorily being necessary.

Another object of the invention is to provide such an unstacking device which is suitable for use in handling open boxes loaded with loose material and which separates the individual boxes from the stack without upsetting the same, thereby retaining said material in said boxes.

A further object of the invention is to provide such an unstacking device which is relatively simple and inexpensive to build and the cost of maintenance of which is low.

The manner of accomplishing the foregoing objects as well as further objects and advantages will be made manifest in the following description taken in connection with the accompanying drawings in which:

Fig. 1 is a side elevational view of a preferred embodiment of the invention.

Fig. 2 is a front elevational view of Fig. 1 taken in the direction of the arrow 2.

Fig. 3 is a plan view of Fig. 2 with the motor removed to permit the structure therebeneath to be visible.

Fig. 4 is a cross sectional view taken on the line 4—4 of Fig. 1.

Fig. 5 is an enlarged diagrammatic view of a section of one of the stack elevating chains and

2

illustrating a chain lock in an inactive position as when the elevator is lifting a stack.

Fig. 6 is a view similar to Fig. 5 and illustrates the chain lock in operation when the elevator is halted.

Fig. 7 is a diagrammatic sectional view taken on the line 7—7 of Fig. 2 and illustrating the manner in which certain electric switches of the device are actuated.

10 Fig. 8 is an enlarged detail view of a stack actuated switch of the invention located at the lower end of the elevator.

Fig. 9 is a diagrammatic detail view illustrating the manner in which a stack supporting crane arm is guided in changing direction at the upper end of the elevator.

Fig. 10 is a diagrammatic view illustrating one position of an uppermost box of a stack just after the action starts by which said box is separated from the rest of the stack.

Fig. 11 is a view similar to Fig. 10 and illustrates a more advanced stage in said box separating action.

Fig. 12 is a wiring diagram showing a preferred 25 electrical wiring system for use in the operation of said invention.

Fig. 13 is a simplified diagram of the same wiring system shown in Fig. 12.

Referring specifically to the drawings the invention is there shown as embodied in an unstacker 25 having a frame 26 the base 27 of which is mounted upon a level floor 28 (Fig. 1) there being a suitable pit 29 formed in said floor to accommodate portions of the structure of the unstacker which extend below the floor line.

35 The base 27 includes longitudinal members 30 which are connected by a cross member 31 and upon which inclined upright channel members 32 and 33 are mounted. The upper end portions of the channel members 33 are angled relatively

40 to the lower portions thereof so as to lie parallel with the channel members 32 and are connected thereto by spacers 34 and 35 (Fig. 1). The channel members 32 are tied together by cross channels 36, 36a and 37. Mounted on these cross channels are stack guides 38. Mounted on inner faces of channels 32 are inner and outer rising flight chain guides 45 and 46 (Figs. 2 and 4).

45 Lower terminal chain guides 47 (Figs. 1 and 2) are also provided which lie on the same planes as the guides 45 and 46. Chain guides 48 and 49 (Figs. 1, 5 and 6) are mounted on the inner faces of the members 33 near their upper ends. Chain locks 50 are pivotally mounted on the guides 49 for operation as illustrated in Figs. 5 and 6.

Journalled in suitable bearings supported between upper ends of the frame members 32 and 33 is a lifter shaft 55 (Figs. 1, 2 and 3) carrying lifter rollers 56 which are preferably provided with rubber treads 57. Fixed on one end of shaft 55 is a sprocket 58 (Fig. 2) and on the other end thereof a sprocket 59.

Projecting laterally from upper ends of the frame members 32 and 33 are box structures 60 carrying bearings 61 and 62 (Fig. 2), stub shafts 63 being journalled in said bearings. Secured on the inner ends of these shafts are sprockets 64 having drums 65 formed thereon. Also fixed on shafts 63 just outside the bearings 62 are sprockets 66.

Trained about the sprocket 64 and extending between the chain guides 45, 49, 48, and 49 and around the reverse turn chain guides 47 (Fig. 1) are endless chains 70. These chains carry two stack cradles 71 each of which includes a pair of individual stack supports 72 mounted on the chains 70 at corresponding points thereon. Each of the supports 72 includes a gib block 73 which is welded to one of the links of one of the chains 70 and has a slot 74 therein which is adapted to receive the adjacent chain guide 48 when that gib is rising with the rising flight of its chain 70 so as to steady the stack support 72 of which it is a part. Said stack support also includes an arm 78 which is pivotally supported on the gib block 73 at 79. The outer end of the arm 78 is connected by a link chain 83 with a link in the chain 70 on which said support 72 is mounted which is several links in advance of the link on which the block 73 thereof is mounted.

Supported at its upper end on plates 81 fixed on channel members 33 is a take-away box conveyor 82 having a frame 83 on the upper end of which is mounted a shaft 84 carrying a pulley 85 about which is trained a conveyor belt 86 the latter riding over an arched apron 87 provided on the frame 83 as said belt travels downwardly. The frame 83 also has a counter shaft 88 which is connected by a chain 89 and suitable sprockets to the shaft 84. The shaft 88 has a sprocket 90 on its extending end which is connected by a chain 91 with the sprocket 59 (see Fig. 2).

Extending forwardly from the upper ends of frame member 32 is a rigid frame structure 95 including horizontal channel members 96, diagonal channel members 97, and angle structures 98 and 99 which are welded together on the upper edges of the members 97. Fixed on the structures 99 are a pair of bearings 100 in which a shaft 101 journals, this shaft carrying at its opposite ends a pair of sprockets 102 and, outside one of these sprockets, a sprocket 103. Trained about and connecting the sprockets 102 with the sprockets 66 are endless chains 104.

Supported on the structure 98 is a geared electric motor 110 which drives sprockets 111 and 112, the sprocket 111 being connected with a sprocket 58 by a chain 113 and the sprocket 112 being connected with the sprocket 103 by a chain 114. Fixed on the frame members 96 to extend downwardly therefrom near their outer ends are housings 120 providing slideways 121 for bearings 122 in which opposite ends of a shaft 123 journal, said housings enclosing coil springs 124 which bias said bearings 122 inwardly against the inner ends of runways 121. The pressure of springs 124 against bearings 122 is adjustable by screw jacks 125 provided on said housings.

Fixed to inside faces of end portions of the frame members 96 are plates 130 having arms 131

and 132 extending downwardly therefrom, the arm 131 being bent outwardly at its lower end to extend under the shaft 123.

Pivoted at their lower ends to lower ends of arms 131 and 132 are links 133 and 134, the upper ends of which are connected by transverse shafts 135 and 136. Pivotally mounted on these shafts, with said shafts in spaced relation, are box pusher members 137 each of which has a fork 138 at its inner end in each of which is pivotally mounted a rubber tired roller 139 which is similar to one of the rollers 56.

Fixed on shaft 123 is a pair of cylindrical metal rollers 140, the rollers 56, 139, and 140 on each side of the machine lying in the vertical plane of the box guide 38 on that side of the machine (see Figs. 2 and 3). The unstacker 25 is adapted to handle boxes B the heads of which rest against the beads 150 of the box guides 38 when a stack 35 of these boxes is symmetrically positioned in the machine. Fixed guides 151 are provided near the upper end of the guides 38 to center the boxes of a stack handled in the machine, as this is lifted therein.

Mounted on the floor 23 for feeding stacks S of boxes B into the machine 25 is a floor track 160 comprising a pair of chains 161, the upper flights of which travel in metal channels 162, and which are driven by sprockets 163 on a shaft 164. The latter shaft is driven by an electric motor (not shown) which is connected thereto by a sprocket 165 and a chain 166. The shaft 164 also has a sprocket 167 which rotates a drive shaft 168 of an auxiliary floor track 169 through a chain 170 which connects sprocket 167 with a sprocket 171 which is fixed on the shaft 168.

Electric controls for the unstacker 25 include a switch s-1 which is mounted on the floor track 160 so as to be opened by a stack S passing thereover; switch s-2 which is positioned to be engaged by the lower end of a stack as the latter is delivered into the unstacker 25; switch s-3 which is located just below one of the frame members 96 and is actuated by a gib 73 each time a cradle 71 rises past said switch; and switch s-4 which is mounted at the upper end of the machine (Figs. 1 and 2) to be engaged by one of the gibs 73 of each cradle 71 as the latter passes over the zenith of its path of travel. It might be noted here that each of the arms 78 has provided thereon a boss 172 which engages the drum 65 of the adjacent sprocket 64 as the gib 73 on which said arm is mounted changes direction at the upper end of the unstacker elevator (Figs. 2 and 9) thereby smoothly reversing the movement of supports 72 about shaft 63.

Mounted on structure 98 is a switch s-17 which is opened whenever a box gets caught on the box therebeneath and thus, failing to be discharged over the rollers 56, rises into contact with a plate 175 supported on a lever 176 which overlies switch s-17 and is pivotally mounted on structure 98. The opening of switch s-17 stops motor 110 until the removal of the box in question permits the unstacker to resume its normal operation, which takes place when switch s-17 is again closed.

OPERATION

Fig. 1 illustrates the unstacker 25 in the act of unstacking a stack S of boxes B. The operation starts by closing the open points of switch s-7 which constitutes the starting and

stopping switch, which energizes the motor 110 and the motor 180 which drives the floor tracks 160 and 169 through the chain 166. Stacks S of boxes B are now placed upon the floor track 160 and these are carried on this track towards the stacker 25. When the motor 110 is energized without any stack being in the unstacker, this motor is halted the first time switch s-4 is opened by a cradle 71 passing over the zenith of its path of movement. At this time the other cradle 71 is at the bottom of the unstacker and the arms 78 thereof are guided by guides 181 so that these turn forwardly into proper positions for lifting a stack S when the latter has been fed into the machine. After the halting of the motor 110 by the actuation of switch s-4 the floor track continues to feed the initial stack S into the machine until the latter engages and actuates switch s-2. This starts the motor 110 causing upward travel of one of cradles 71 immediately beneath the stack in the unstacker.

If switch s-1 remains depressed while the initial stack S is engaging switch s-2 the floor track motor 180 is halted and remains de-energized until the gib 73 of the support 72 on that side of the unstacker engages switch s-3 whereupon the motor 180 is re-energized causing the floor track to resume the delivery of stacks S to the unstacker 25.

As the uppermost box of a stack S being elevated in the unstacker 25 comes opposite the rollers 140 the upper box B therein is forced inwardly against the beads 158 of the box guides 38 so that the corners of the box disposed inwardly will engage the rubber tired rollers 56 when this box comes opposite said rollers. This results as shown in Fig. 10 in the inner portion of the box B, thus engaging the lifter rollers 56, being lifted upwardly while the outermost portion of this box B still rests upon the box immediately there beneath.

About the same time said uppermost box comes into contact with the rollers 56 it also engages the rollers 139 of the pusher members 137 so as to lift the rollers 139 upwardly and swing the members 137 outwardly so that rollers 139 move away from over said uppermost box until said rollers arrive in an inwardly pushing position in which they are shown in Fig. 10. This movement of rollers 139 stretches the springs 190 which are connected at their opposite ends to the structure 98 and shaft 136. This positioning of the rollers 139 and stretching of the springs 190 is followed shortly by the inner portion of the uppermost box B being lifted by the rollers 56 into a position to pass over these rollers 56 which is accompanied by considerable acceleration due to the frictional engagement of the rollers 56 with the uppermost box B and the inward pressure of the rollers 139, urged, as these rollers are, by the tensioned springs 190.

The rollers 139 follow the uppermost box B inwardly as shown in Fig. 11 until the center of gravity of said box is almost directly over the axis of the rollers 56 and the movement of this box over the rollers 56 has been accelerated to the point where it is rapidly discharged from over these rollers onto the conveyor 82.

In like manner each of the succeeding boxes 70 of the stack S in the unstacker 25 is discharged singly over the rollers 56 and onto the conveyor 82.

A significant advantage of the present invention is to be found in the fact that the mechanism for separating individual boxes, from the upper 75

end of a stack of the same being elevated, does not operate in timed relation with the elevator but instead operates in timed relation with the contact of the upper face of the uppermost box 5 with the rollers 139. Considering the lifter rollers 56 and the stack guides 38 as "guide means" disposed alongside the rising stack, it is to be noted that irrespective of variations in the depth of the boxes B (within a reasonable range, of course), the box separating mechanism functions in timed relation with the engagement of the upper face of each uppermost box B with the rollers 139 to effect separation of this box from the stack and the discharge thereof over said 10 guide means, as shown in Fig. 11. The unstacker 25 is thus adapted for use on boxes varying as much as an inch in depth without causing any malfunctioning of the individual box separating mechanism at the upper end thereof. In prior 15 unstackers this would be impossible because of the mechanical drive connection provided therein between the elevator and the box separating mechanism so that these operated in only a single fixed timed relation with each other.

20 25 It is to be noted, therefore, that the rollers 139 perform three functions. They act as timing members in that they cause the box separating mechanism to function to separate the uppermost box from the stack in what is practically a fixed 30 timed relation between said separation and the moment said upwardly moving box contacts said rollers. These rollers also perform the function of transmitting from the rising stack the power for stretching the springs 190 and thus imparting 35 to these springs the motive power for separating the box and the stack when the separating mechanism is free to act. Finally, rollers 139 roll over the upper outer corner of said uppermost box as shown in Fig. 10 so as to come into position 40 alongside said box at the moment that its opposite side rises above the lifter rollers 56 whereby rollers 139 transmit to said box the impulse of the box separating mechanism so as to rapidly shift said box out of the path, along which the stack is rising, to a position over the rollers 56 45 the constant rotation of which completes the separation of said box from the stack initiated by the box separating mechanism.

The rollers 56 may thus be considered, in a sense, to comprise part of the box separating mechanism as well as forming a part of the guide means aforesaid.

50 The electrical system shown in Figs. 12 and 13 functions, in the operation of the invention above described, in the following manner. Closing the normally open contacts of starter switch S-7 energizes relay coil S-9-c closing relay contacts S-9-0, S-9-2 and S-9-3 thereby sealing in the energizing circuit of coil S-9-c. The closing of 55 switch S-9-3 energizes the elevator motor switch coil S-13-c starting elevator motor 110. The closing of switch S-9-0 energizes the floor track motor switch coil S-12-c thereby starting floor track motor 180. A stack resting on the floor track will now be moved toward the unstacker.

60 65 This stack opens switch S-1 upon contacting the same, thereby de-energizing S-12-c and stopping motor 180 with the stack resting on switch S-1 and holding this open. Assuming that one elevator cradle 71 is now below switch S-3 and rising, the gib 73 of that cradle momentarily closes switch S-3, as it passes the same, thereby energizing S-10-c and closing S-10-1 and S-10-2 which re-energizes S-12-c and restarts the floor

track motor 160. The feeding of stack S toward the elevator is thus resumed.

Arriving in the elevator, this stack operates switch S-2, opening the normally closed terminals thereof, which stops motor 160, and closing the normally open terminals with no result as S-13-c is already energized. After its engagement with switch S-3, the rising elevator cradle 71 continues upwardly and, at its zenith, engages switch S-4 which opens this switch with no effect because S-2 is at that time actuated by the entering stack. Had this stack not yet arrived in the elevator, switch S-2 would be unactuated and the opening of S-4 would stop the elevator by de-energizing S-13-c. In such an event the elevator would have remained stopped until the stack engaged S-3 and would then have started. The lower cradle 71 now rises beneath and lifts the stack in the elevator and moves said stack away from S-2 thereby returning the latter to normal. This does not happen however until movement of the adjacent gib 73 of the upwardly disposed cradle out of engagement with switch S-4, closes the latter and this keeps the elevator going.

Switches S-11 and S-11-a are installed a distance apart slightly greater than one box length along the box discharge conveyor 82 so that each of these is contacted and held open by a box as long as said box is directly opposite it. As the boxes are normally spaced apart these two switches will be both open only when a jam occurs on the box discharge conveyor and their simultaneous opening will de-energize S-13-c and stop the elevator. As soon as this jam is relieved and one of the switches S-11 and S-11-a closes as a result, this will re-energize S-13-c and start the elevator.

Switches S-12-T and S-13-T are overload cut-outs incorporated respectively in the magnetic switches for the motors driving the elevator and floor track. In case of an overload on either motor, these overload switches operate to stop both motors.

Switches S-14 and S-15 are manual switches for jogging respectively the motor for the elevator and the motor for the floor track.

The claims are:

1. In a box unstacker, the combination of: an elevator adapted to lift a stack of boxes in column form along a path aligned with said stack; a power driven rotary frictional box lifter located horizontally adjacent an upper portion of said path so that a side portion of an uppermost box on said stack comes into frictional engagement with said lifter and is lifted by the latter; a member disposed in said path so as to be contacted by said uppermost box as it rises therein; means for yieldably mounting said member to cause it to move, in response to engagement of said uppermost box with said member, to shift said member out of said path on the opposite side of the latter from said lifter; means operating to press said member against a side portion of said box opposite that side portion thereof which engages said lifter, whereby said member propels said box onto said lifter and the rotation of said lifter causes the movement of said box thereover to continue until said box is entirely removed from said path; and conveyor means for successively receiving boxes thus delivered from the upper end of said stack and over said lifter.

2. A combination as in claim 1 in which said member is provided with a pair of rollers which

engage the uppermost box of said stack in the planes of the box heads.

3. A combination as in claim 2, in which the means for mounting said member includes linkage constraining the movement of said member to travel between a position in which it overlies and contacts said uppermost box, and a position disposed upwardly from the first position and outwardly away from over said uppermost box, and spring means constantly urging said member from said second position to said first mentioned position.

4. In a box unstacker, the combination of: a stack elevator; a rotary conveyor roller located horizontally alongside the path along which a stack of boxes is lifted by said elevator; power means to rotate said roller with the surface thereof rising adjacent said path; a box pusher member disposed in the path of said uppermost box as it rises toward the level of said roller; and resilient means for mounting said pusher member to cause it to resistingly yield upwardly, when engaged by said box, and away from over said box on the opposite side of said path from said roller, said means thereupon applying pressure horizontally through said pusher against said box, as the latter rises further, to propel said box onto said roller whereby frictional engagement of said box and said roller conveys said box over said roller.

5. A combination as in claim 4 in which said conveyor roller and said pusher each includes a pair of rollers engaging said box in the planes of the box heads.

6. A combination as in claim 5 in which said conveyor rollers have friction treads and engage and lift an adjacent side portion of an uppermost box above the next box therebeneath as said pusher rollers are yielding upwardly and outwardly from over upper edges of said box sides.

7. A combination as in claim 6 in which inclined stack guides are provided in said planes beneath said conveyor rollers, said elevator lifting said stack while tilted against said guides; and a pair of pressure rollers resiliently pressing said next box against said guides as the uppermost box is being engaged by said conveyor rollers and pusher rollers.

8. In a box unstacker the combination of: a stack elevator for elevating a stack of boxes along a given path; a conveyor disposed at a given level alongside said path for successively receiving the boxes of said stack as said boxes arrive at said level; a box pusher disposed in said path to be engaged by the topmost box of said stack as it rises toward said level; and resilient means for mounting said pusher to cause it to resistingly yield upwardly when engaged by said box, and away from over said box on the opposite side of said path from said conveyor, said means thereupon applying pressure horizontally through said pusher against said box, to propel said box onto said conveyor said pusher thereby being again extended into said path so as to be similarly engaged by the next uppermost box of said stack so that the action of said pusher aforesaid is repeated on each of the boxes of said stack as they successively become the topmost box of the stack and are elevated toward the level of said conveyor.

9. In a device for breaking down a stack of articles superimposed one upon another in the form of a column, into a series of separate articles, the combination of: an elevator for lifting

said stack of articles in column form along a path aligned with said stack; guide means disposed along one side of said path for engagement by said stack as said stack rises on said elevator; roller means; means for mounting said roller means to suspend the same in said path so as to be contacted by the uppermost box of said stack as the latter is lifted by said elevator, said mounting means being yieldable, upon movement thus being imparted to said roller means, to guide said roller means along a course which is inclined upwardly and outwardly from said path on the opposite side of the same from said guide means; and resilient means connected with said mounting means so as to resist the travel of said roller means in response to the engagement of said uppermost box with the latter whereby power is transmitted from said elevator through said uppermost box and said roller means to said resilient means, which power is applied reactively through said roller means to a side portion of said uppermost box as said roller means is shifted away from over said uppermost box and as the latter rises above said guide means to cause said power applied to said box through said roller means to propel said uppermost box from said path over said guide means.

10. A combination as in claim 8 in which the return of said pusher into said path rapidly propels said uppermost box onto said conveyor, said pusher remaining in contact with said uppermost box and pushing the latter until the center of gravity of said uppermost box has closely approached a position over said conveyor, thereby assuring that travel of said uppermost box on said conveyor away from over said stack continues after the top face of the next rising box engages and retracts said pusher away from the aforesaid uppermost box to start the next box separating cycle.

11. In a device for breaking down a stack of rectangular boxes, having a uniform cross-section, and superimposed one upon another in the form of a column, into a series of separate boxes, the combination of: an elevator for lifting said

stack of boxes along a path aligned with said stack; a conveyor roller positioned adjacent said path to be frictionally engaged by one side of each box in said stack as said box rises to the level of said roller; means for constantly rotating said conveyor roller; a pair of pusher rollers lying in the planes of the ends of said boxes; means for shiftably mounting said pusher rollers with the latter initially in a position over the ends of the uppermost box so as to extend approximately half way across said ends towards said conveyor roller from the opposite side of said box, said pusher rollers being shifted upwardly and away from said conveyor roller by the rising of said uppermost box while said box is in contact with both said conveyor roller and said pusher rollers until said pusher rollers ride away from over said uppermost box so as to bear against said opposite side of said uppermost box; and yieldable means biasing said pusher roller mounting means to continually urge said pusher rollers towards their first mentioned position, aforesaid, whereby said pusher rollers, upon yielding away from over said box ends, push said box against said conveyor roller, thereby producing a sufficient frictional engagement between said first mentioned box side and said conveyor roller to lift said side of said box causing said side to ride up onto said conveyor roller, the pressure of said pusher roller against the other side of said box thereupon propelling said box over said conveyor roller until said pusher roller has been returned to its initial position, aforesaid, at which time the center of gravity of said uppermost box has closely approached a position directly over said conveyor roller.

ERNEST A. VERRINDER.
